CLAIM

The ornamental design for a cart for holding rolls of wire, as shown and described.

DESCRIPTION

FIG. 1 is a side elevation view of a cart for holding rolls of wire showing our new design the opposite side being a mirror image thereof, it being understood that the broken lines are for illustrative purposes only;

FIG. 2 is a sectional view thereof taken along line 2—2 in FIG. 1;

FIG. 3 is a right end elevation view of FIG. 1, the left end being substantially a mirror image thereof; and

FIG. 4 is a top plan view thereof.
